Specification for Design.

Patented Sept. 13, 1921.

Application filed March 16, 1921. Serial No. 452,766. Term of patent 7 years.

To all whom it may concern:

Be it known that I, CHESTER LAURENCE SUMNER, a citizen of the United States, and a resident of Tacoma, in the county of Pierce and State of Washington, have invented a new, original, and ornamental Design for Handkerchiefs, of which the following is a specification, reference being had to the accompanying drawing, forming part thereof.

The figure is a plan view of a handkerchief embodying my new and ornamental design.

I claim:

The ornamental design for a handkerchief, as shown.

CHESTER LAURENCE SUMNER.
